CLAIM

The ornamental design for a paint tray assembly, as shown and described.

DESCRIPTION

FIG. 1 is a perspective view of a paint tray assembly, from the top, front and left side thereof;

FIG. 2 is a front view thereof;

FIG. 3 is a rear view thereof;

FIG. 4 is a side view thereof (as taken from the left side in FIG. 2);

FIG. 5 is a side view thereof (as taken from the right side in FIG. 2);

FIG. 6 is a top view thereof; and,

FIG. 7 is a bottom view thereof.
